Fig. 6.

Fig. 7.

Fig. 8.

FIG. 1 is a perspective view of a combined toilet bowl and seat showing my new design, with the seat cover in a raised position;

FIG. 2 is a top plan view thereof with the seat cover closed;

FIG. 3 is a right side elevational view thereof, the left side being a mirror image of the right side except for the pedal;

FIG. 4 is a front elevational view thereof;

FIG. 5 is a rear elevational view thereof;

FIG. 6 is a rear elevational view of a modified form of the combined toilet bowl and seat shown in FIG. 1;

FIG. 7 is a right side elevational view of FIG. 6, the left side being a mirror image of the right side except for the pedal; and

FIG. 8 is a front elevational view of FIG. 6.

I claim:

The ornamental design for a combined toilet bowl and seat, as shown and described.
